[57] CLAIM

The ornamental design for the maxillary orthopedic suture separating orthodontic appliance, substantially as shown and described.

DESCRIPTION

FIG. 1 is a bottom plan view of a maxillary orthopedic suture separating orthodontic appliance showing my new design and with the patient's teeth being shown in broken lines for illustrative purposes only;

FIG. 2 is a front elevation view of the appliance shown in FIG. 1;

FIG. 3 is a side elevation view of the appliance shown in FIGS. 1-2; and

FIG. 4 is a front elevation view of a modified form of appliance in accordance with my new design.
